UNITED STATES PATENT OFFICE.

WILTON ELMORE DARROW, OF SONORA, CALIFORNIA.

DEVICE FOR COLLECTING FINELY-DIVIDED MINERALS AND SLIMES.

SPECIFICATION forming part of Letters Patent No. 660,844, dated October 30, 1900.

Application filed February 23, 1900. Serial No. 6,231. (No model.)

To all whom it may concern:

Be it known that I, WILTON ELMORE DARROW, a citizen of the United States, residing at Sonora, county of Tuolumne, State of California, have invented an Improvement in Devices for Collecting Finely-Divided Minerals and Slimes; and I hereby declare the following to be a full, clear, and exact description of the same.

10 My invention relates to an improved apparatus for concentrating and collecting high-grade mineral.

It consists of submerged inclined surfaces upon which said mineral is concentrated and 15 a means for precipitating and eliminating heavy waste gangue, while the fine particles in suspension flow on with the water and may be collected in reservoirs for future treatment.

20 My invention also comprises details of construction which will be more fully explained by reference to the accompanying drawings, in which—

Figure 1 is a longitudinal section through 25 the center. Fig. 2 is a plan view. Fig. 3 is an end view partially in section. Fig. 4 is a detail view showing a portion of one of the cords 7.

30 In the milling of ores large quantities of valuable minerals are so finely pulverized that they remain in suspension in the water and cannot be collected either on vanners or canvas or other belts. In fact, some of the material will remain in suspension in still wa- 35 ter for days. I have discovered that in working gold ores a large part of this fine mineral may be concentrated on submerged inclined surfaces as high-grade product, while the fine material that still remains in suspension in 40 the water after being separated from the heavy waste gangue will assay approximately the same as the original ore.

45 Various devices may be employed in carrying out my invention. In the present drawings I have illustrated one means for effecting the desired result; but it will be manifest that the inclined surfaces may be variously arranged to suit conditions or the desires of the user.

50 As here shown, A represents a tank-receptacle or generally any inclosed space within which the inclined surfaces 2 are fixed.

3 is a sluice for supplying the material to be concentrated, and 4 is the overflow discharge-slue through which the water and fine slimes pass out, this discharge being upon 55 about the same level with 3.

5 is a distribution-box as a means for admitting the material uniformly and gently into the head of the apparatus. 60

The inclined surfaces 2 for collecting and saving the high-grade material are submerged in the water within the space into which it is admitted through the distributing box. They may be made of any suitable material— 65 such as thin lumber, canvas, or the like—and are placed at an angle of between forty-five and ninety degrees or on such a slant that the heavy gangue will slide off. The bottom of this space or chamber is formed 70 with a corrugated or channeled floor 6, having apertures or orifices at the bottom or apex of each of the channels, through which the gangue is allowed to escape. The object of this floor is to confine the circulation of wa- 75 ter carrying mill-tailings to the upper compartment, where it may flow slowly over the submerged inclined surfaces. These openings are normally closed during this operation by valves or stoppers of any suitable de- 80 scription. I have here illustrated a suitable form of stopper, consisting of flexible cords 7, extending above the transverse slits or openings 8, and when these are lowered they stop the openings and prevent the tailings in 85 the upper compartment from passing down into the lower compartment 9, into which these apertures open. This is for the purpose of preventing their escape when the discharge-gate 90 is opened. The apertures may be of any shape and size, and any suitable device other than that described may be employed for closing them without altering the character of the invention. The openings are large enough to 95 permit the escape of heavy material and preventing it from building up around the inclined surfaces. When the apparatus is in use, both upper and lower chambers are filled with water and the sand or heavy gangue dropping into these troughs or compartments 6 will pass 100 down through the apertures into the lower compartment and accumulating therein may be discharged at suitable intervals. The floor of this compartment preferably converges to

a common center and is also inclined longitudinally to a discharge-gate 10, through which the sand or gangue may be discharged at suitable intervals.

5 11 is a water pipe or pipes extending within the chamber 9 and numerously perforated, so that water discharged therefrom will assist in sluicing out the material which is collected in this chamber.

10 The operation of the apparatus will be as follows: The discharge-gate 10 being closed the apertures in the corrugated floor 6 are opened. Clear water is then admitted through the pipe or pipes 11 and will first fill the lower 15 compartment, thence rising up through the apertures and submerging the inclined surfaces and filling the entire apparatus. The supply of clear water is then nearly or quite cut off. The tailings are admitted and flow 20 slowly through the receptacle. A part of the fine material will adhere to the submerged inclined surfaces, while the heavy material will sink to the bottom and will pass through the openings in the corrugated bottom or floor 6,

25 settling in the lower compartment or compartments. The very light material which remains in suspension is carried on by the water and discharged through the overflow or discharge gate 4 and may be collected in 30 reservoirs for future treatment. If there is a tendency for valuable suspended material to settle down with the gangue, it may be prevented from doing so by maintaining a continual flow of clear water from the pipes in 35 the chamber below, and this water rising through the openings into the upper compartment acts as a hydraulic classifier. When the lower compartment becomes filled with the waste material and requires dis-

40 charge, the apertures above are closed, a discharge-gate 10 is opened, and a large volume of clear water admitted through the pipe or pipes 11, and the gangue or waste material is thus sluiced out. The discharge-gate is then 45 closed, the lower compartment is again filled with clear water, thus balancing and relieving the downward pressure from above, and lastly the apertures are opened and the operation continued.

50 When the inclined surfaces become charged with fine mineral, which can be noted by inspection, they may be removed in sections, cleaned, and replaced without interrupting the continued operation of the apparatus, or, 55 if desired, the tailings may be turned off and the accumulated sand discharged, as above described, after which the inclined surfaces may be washed off, the product passing out through the discharge-gate 10 and collected 60 in suitable receptacles.

Having thus described my invention, what I claim as new, and desire to secure by Letters Patent, is—

1. An apparatus for collecting finely-divided mineral and separating it from heavier gangue comprising a stationary tank having upper and lower compartments and a floor

separating one compartment from the other and corrugated transversely, said upper compartment having an inlet at one end portion 70 and an overflow at the opposite end portion, a series of superposed collecting-surfaces submerged beneath the surface of the water in the tank and extending in the direction of the flow of the water through said tank, said surfaces inclined toward the longitudinal sides of the tank whereby heavy material will slide off the surfaces by gravitation and be delivered in the channels formed by the corrugated floor, and the lighter material will adhere to 80 said surfaces.

2. An apparatus for separating finely-divided material from heavier gangue and collecting it comprising a tank having a bottom inclined laterally and also inclined longitudinally to a point of discharge, a transversely-corrugated floor in the tank and dividing the latter into upper and lower compartments, superposed collecting-surfaces in the upper compartment below the surface of the water 90 and extending in the direction of the flow of the latter, and inclined toward the longitudinal sides of the tank, said upper compartment having an inlet and overflow, means for admitting water to both compartments, passages 95 connecting the two compartments and means controlling said passages.

3. An apparatus for separating finely-divided material from heavier gangue and collecting it, consisting of a stationary tank or 100 receptacle having supply and discharge passages, transversely-inclined collecting-surfaces fixed therein, and disposed in vertical series, means for supplying water from a plurality of points upwardly in the vertical plane 105 of the plates whereby inclined surfaces are constantly submerged, and means including transversely-extending channels below the surfaces for collecting and discharging the heavy gangue without disturbing the inclined 110 surfaces and their load.

4. An apparatus for separating finely-divided mineral from heavier gangue consisting of a stationary tank or space having surfaces inclined toward the longitudinal sides 115 of the tank so that heavy material will slide therefrom and lighter material will collect thereon, means for supplying water from below to fill the tank and submerge the surfaces, means for supplying material to pass 120 through the tank and over the surfaces, and a discharge at the opposite end, a transversely corrugated or channeled bottom having openings therethrough and a closed receptacle beneath which is also filled with water whereby 125 the heavy sediment gradually passes through the openings into the lower compartment without agitation in the upper compartment.

5. An apparatus for collecting finely-divided material and separating it from heavier 130 gangue, consisting of a stationary tank or receptacle having transversely-inclined surfaces and transversely corrugated or channeled bottom with apertures therethrough, a

closed chamber or chambers beneath, with which said apertures communicate, and a gate or gates through which said chamber may be periodically discharged, valves or stoppers closing the passages between the two chambers when the lower chamber is to be discharged, and pipes through which water is admitted into the lower chamber and caused to rise and fill the upper chamber.

10 6. A means for concentrating and saving fine suspended mineral contained in mill-tailings, consisting of a tank having upper and lower compartments, stationary, submerged,

transversely-inclined surfaces in the upper compartment, and means for delivering up-flowing currents of water directly under the surfaces, from the lower compartment, whereby the products of different specific gravity are separated.

In witness whereof I have hereunto set my hand.

WILTON ELMORE DARROW.
